ATTORNEYS

UNITED STATES PATENT OFFICE.

ELIZABETH GUENTHEAN GILES, OF LOCKPORT, NEW YORK.

POWDER PUFF.

Application filed June 30, 1922. Serial No. 571,964.

To all whom it may concern:

Be it known that I, ELIZABETH G. GILES, a citizen of the United States, and a resident of Lockport, in the county of Niagara and 5 State of New York, have invented a new and Improved Powder Puff, of which the following is a full, clear, and exact description.

This invention relates to improvements in 10 powder puffs, an object of the invention being to provide a powder puff which comprises a receptacle for powder and which is provided with draw strings having applicator puffs at the ends of the draw strings. 15 so that said applicator puffs can be enclosed within the receptacle when the latter is closed.

A further object is to provide a powder puff which is extremely ornamental and attractive in appearance and which embodies many features of advantage not heretofore known.

With these and other objects in view, the invention consists in certain novel features 25 of construction and combinations, and arrangement of parts, as will be more fully hereinafter described and pointed out in the claims.

In the accompanying drawings—

30 Figure 1 is a perspective view showing the powder puff in open position.

Figure 2 is a similar view showing the powder puff in closed position.

Figure 3 is a view in longitudinal section.

35 Figure 4 is a fragmentary view in side elevation illustrating the manner of connecting the draw strings to the receptacle.

Figure 5 is a sectional view of one of the applicator puffs.

40 1 represents a powder puff, which to distinguish the same from a pair of applicator puffs 2, I shall hereafter refer to as the main powder puff. This main powder puff 1 is composed preferably of white or tinted wool, 45 and to the skin 3 of the wool I secure a ribbon 4, the ribbon being sewed to the edges of the skin as shown at 5 and the ends of the ribbon joined in any approved manner to form a powder receptacle 6.

50 The outer open end of the receptacle 6

is closed by a pair of draw strings 7 and 8. These draw strings being laced through the selvage of the ribbon at a point below the edge thereof, so as to prevent the necessity of providing a seam and also giving an ornamental finish to the material. 55

The applicator puffs 2 are secured to the ends of the draw strings 7 and 8 respectively so that they are in convenient position for using the powder in receptacle 6, the main 60 puff 1 being used to spread, or finish the application by the applicator puffs 2.

Before the receptacle is closed, the applicator puffs 2 are inserted within the receptacle, and are effectively inclosed therein 65 when the draw strings are pulled tightly, the ends of the draw strings serving as loops for carrying the main puff if desired.

Various slight changes might be made in the general form and arrangement of parts 70 described without departing from my invention, and hence I do not limit myself to the precise details set forth, but consider myself at liberty to make such changes and alterations as fairly fall within the spirit and 75 scope of the appended claims.

I claim:

1. As a new article of manufacture, a main powder puff having a receptacle thereon of flexible material, draw strings for closing said receptacle, and applicator puffs at 80 the ends of the draw strings.

2. As a new article of manufacture, a main powder puff having a receptacle thereon of flexible material, draw strings for 85 closing said receptacle, applicator puffs constituting anchors at the ends of the draw strings, said applicator puffs adapted to be confined within the receptacle when the latter is closed by the draw strings whereby 90 said draw strings function as supporting loops on the main powder puff.

3. A device of the character stated, comprising a powder puff having a skin backing, a receptacle of flexible material secured 95 to the skin backing, draw strings laced through the flexible material, and applicator puffs at the ends of the draw strings.

ELIZABETH GUENTHEAN GILES.
